UNITED STATES PATENT OFFICE.

ERNST TAUBE, OF ST. PAUL, MINNESOTA.

DESIGN FOR A PICTURE-FRAME.

No. 40,060.

Specification for Design.

Patented June 15, 1909.

Application filed December 18, 1908. Serial No. 468,237. Term of patent 14 years.

To all whom it may concern:

Be it known that I, ERNST TAUBE, a subject of the Emperor of Germany, residing at St. Paul, in the county of Ramsey and State of Minnesota, have invented a new, original, and ornamental Design for a Picture-Frame, of which the following is a specification.

In the accompanying drawing Figure 1 is a front view of a frame embodying my design, and adapted as a frame for either mirrors or pictures. Fig. 2 is an edge view of a portion of the frame in Fig. 1 looking from left to right.

The object is to please the eye by an ornamental artificial configuration resembling

closely a rustic picture frame made of natural, old, partly decayed wood ripped into half round strips 1 and having on it the wrinkled and cracked bark 2, with moss 3 grown thereon, and fungi 4, brier 5 and stumps 6 of branches or twigs upon the surface, as shown.

I claim:

The ornamental design for a picture frame, as shown and described.

ERNST TAUBE.
